No. 12, 718

Jan. 31, 1882

UNITED STATES PATENT OFFICE.

FRANK H. HOTCHKISS, OF BIRMINGHAM, CONNECTICUT.

DESIGN FOR A CLOCK.

SPECIFICATION forming part of Design No. 12,718, dated January 31, 1882.

Application filed November 7, 1881. Term of patent 7 years.

To all whom it may concern:

Be it known that I, FRANK H. HOTCHKISS, a citizen of the United States, residing at Birmingham, in the county of New Haven and State of Connecticut, have originated and invented a new and useful Design in Clocks; and I do hereby declare that the following is a full, clear, and exact description thereof, reference being had to the accompanying photograph, forming a part of this specification.

The design for a clock and its supporting base consists essentially, as shown by the accompanying photograph, in forming the same in the general shape or configuration of a hose-carriage such as is used by fire-departments.

In the photograph herewith, A represents the reel upon which the hose is coiled. In the present instance this reel-like portion serves as the clock-case within which the operative mechanism of the clock is contained.

B represents the gong used upon such carriages, which in the present instance is suspended from an upright, a, on the reel, and serves as the bell upon which the hours or portions of hours are struck by the clapper or hammer C.

D D represent the wheels of the carriage, which may be of the design here shown, or

simply plain or ornamented in any other suitable manner, as desired.

The clock-case A is supported upon extensions b, which, when the wheels are designed to revolve, extend inward from the axles of the respective wheels, but when the wheels are constructed with incapacity for revolving may extend from the center c, or any desired portion thereof.

E represents the draft-pole. This representation of a hose-carriage may, when it is designed that the wheels D shall be incapable of rotation, be supported upon a base or platform, F, in which event the feet G, upon which said base F rests, may be representations of firemen's helmets, as shown.

What I claim is—

A design for a clock, consisting of the representation of a fireman's hose-carriage, substantially as shown and described.

In testimony that I claim the foregoing as my own I affix my signature in presence of two witnesses.

FRANK H. HOTCHKISS.

Witnesses:

OSCAR D. ROGERS,
F. S. HASKELL.
